CLAIM

The ornamental design for a shelf, as shown and described.

DESCRIPTION

FIG. 1 is a perspective view of a shelf showing my new design;

FIG. 2 is a front elevational view of the shelf seen in FIG. 1;

FIG. 3 is a rear elevational view of the shelf seen in FIG. 1; FIG. 4 is a right side elevational view of the shelf seen in FIG. 1, the left side elevational view being a mirror image thereof;

FIG. 5 is a top plan view of the shelf seen in FIG. 1; and, FIG. 6 is a bottom plan view of the shelf seen in FIG. 1. In the drawings, the broken lines depict portions of the shelf that form no part of the claimed design. Shade lines, having a combination of long and short lines in the drawings, show contour and not surface ornamentation.
